UNITED STATES PATENT OFFICE.

RUDOLF GRUNDMAN, OF CHICAGO, ILLINOIS.

RAILROAD TRACK-SCALE.

1,168,496.

Specification of Letters Patent. Patented Jan. 18, 1916.

Application filed November 17, 1914. Serial No. 872,582.

To all whom it may concern:

Be it known that I, RUDOLF GRUNDMAN, a citizen of the United States of America, and a resident of Chicago, county of Cook, and 5 State of Illinois, have invented certain new and useful Improvements in Railroad Track-Scales, of which the following is a specification.

The main objects of this invention are to 10 improve the construction of track scales to overcome their tendency to become inaccurate, due to jars received when loading or spotting cars thereon.

Another object of the invention is to provide 15 an improved construction of bearing for the scale platform, saving the scale levers from lateral jars or endwise displacement during the process of weighing.

Another object of the invention is to provide 20 an improved arrangement of platform supporting levers and mechanism for transmitting movement from these levers to a scale beam, permitting exceedingly high multiplication in the levers which directly 25 support the platform and permitting an improved arrangement of fulcrums and bearings for the levers, saving these levers from lateral strains due to impact on one side or the other of the scale when cars are rolled on 30 the platform.

Another object of the invention is to provide 35 an improved construction of platform, permitting it to be slightly but uniformly flexible along its length and preventing it from being raised from its bearings at one point when supporting a heavy load at some other point.

Another object of the invention is to provide 40 an improved dirt shield or cover for the slots in the scale deck, permitting considerable relative movement between the deck and live rails without interfering with the weighing operation.

An illustrative embodiment of this invention 45 is shown in the accompanying drawings, in which—

Figure 1 is a longitudinal vertical section, partly broken away, and taken on the line A—A of Fig. 2, of one section of the improved scale. Fig. 2 is a plan view of the scale pit and scale levers mounted therein. Figs. 3 and 4 are longitudinal vertical sections partly broken away, taken on the line B—B of Fig. 2. Fig. 5 is a plan view of the scale. 55 Fig. 6 is a transverse section taken on the line C—C of Fig. 2. Fig. 7 is a transverse

vertical section taken on the line D—D of Fig. 2. Fig. 8 is a transverse vertical section taken on the line E—E of Fig. 2. Fig. 9 is a detail of the platform frame. Figs. 60 10 and 11 are fragmentary details of the rail dirt shield. Figs. 12, 13 and 14 are respectively end, side and plan views of a bearing between the platform and a main supporting lever.

Railroad track scales, as usually constructed, have the main bearings located in vertical alinement with the live rails mounted on the platform, subjecting the scale to uneven strains, as it is found that the load or force 70 of the weight is not directly downward but spreads outwardly and therefore requires that the main platform bearings be located outside the plane, passing through the tracks. The present invention, having bearings arranged in the manner last mentioned, improves the suspension of the scale platform, preventing racking effects in the platform and its bearings and preventing undesired disturbances in the scale levers during 75 the process of weighing.

In many track scales, the main supporting levers extend transversely of the scale platform and have a tendency to shift in their bearings as the result of impact of cars, usually in one direction, on the scale tracks. This shifting or kicking of the main levers and also of the middle extension levers especially, causes their pivots to wear sidewise, throwing them out of seal and changing 80 distances between the pivotal centers. The pivots frequently become loose, especially when oiled, making the levers still further inaccurate.

Some scales are provided with main levers 95 which extend longitudinally of the scale platform, but have not been arranged in a manner to overcome the defects mentioned, particularly when the so-called pipe levers are employed. These, because of the arrangement of the platform bearing pivot out of alinement with the end bearings, are particularly subject to lateral or racking strains, when the wheels on one side of the car truck strike the platform track ahead of 100 the wheels on the opposite side.

The common form of track scales having the main supporting levers running crosswise in the scale pit are objectionable because of their short length, the multiplication being low and bringing an undue load 110 on the end extension and middle extension

levers to which the main levers are directly connected. While cars are moving over the scales, two trucks of two different cars get between the first and second section, bringing a heavy load or unexpected strain on the main pivot of the middle extension lever, which, because of the arrangement of multiplication, carries a large portion of the load.

A construction frequently found in prior railroad track scales, and which it is desired to improve, is that the platform girders running parallel with the track are either each in one piece or when spliced, the splices are arranged in staggered relation, providing a practically rigid platform. With such arrangement it is found that when one truck with a heavily loaded car is passing over the middle of the scale, it springs the platform between the center sections, the ends of the platform rise and get loose on their bearings, causing the next truck of the car to hit the loose end of the platform and wear the pivots considerably.

The present invention provides a substantially but not wholly rigid scale platform, being built in sections with the girder sections spliced or bolted together above the platform pivots. The splices of the two main longitudinal girders are in transverse alignment, thus dividing the platform into a plurality of sections and these sections are provided with angular reinforcements, thus making each section of the platform exceedingly rigid while permitting said sections to have some extremely slight pivotal relative movement around the bolts in the splices immediately above the supporting bearings.

Referring to the drawings, particularly Fig. 8, a scale pit 1 is shown formed of concrete walls 2 and supporting embedded therein a plurality of rigid I-beams 3 extending transversely over the scale pit. These beams support the usual flooring or deck 4 carrying the dead rails 5 for permitting passage of cars without disturbing the scale. The deck 4 is provided with the longitudinal openings 6 through which the stands 7 extend for supporting the live rails 8. Stands 7 are mounted on the platform ties 8.1, which in turn are supported by the platform girders 9. These girders are made of sections connected together by the splices 10 (Fig. 1) bolts being employed to secure the girder sections together in preference to rivets or other means preventing some slight relative movement between the sections. The splices in the two girders are in alignment transversely of the scale and the opposite girder sections are connected together by obliquely extending stays 11 (Figs. 8 and 9). By this construction, the scale platform is divided into a plurality of rigid sections, said sections being secured together but having an extremely slight relative hinge action under extremely heavy loads.

The platform bearings 12 are preferably located at the ends of the platform and immediately below the splices 10 in girders 9, eight platform bearings being provided in the four section scale shown in the drawings.

The bearings 12 comprise a plurality of superimposed ball bearings permitting a limited horizontal movement in any direction of the scale platform and having practically no tendency to transmit transverse or obliquely directed jar movements to the main supporting or multiplying levers 13. The lower bearing member 14 of bearings 12 is provided with a V-shaped recess 15 for resting upon the usual knife edge 16 carried by a lever 13. The bearing member 14 is provided with suitable seats for a set of balls 17 of suitable number, preventing a relative tilting between the bearing members 14 and 18. Above the ball 17 is an intermediate bearing member 18 which receives the load of the scale platform through two balls 19 between the member 18 and the bearing member 20 rigidly secured to girders 9. The intermediate bearing member 18 is made in two parts bolted together, as shown in Figs. 12 to 14 to permit a slight relative movement between the two halves of the member 18, for the purpose of insuring that contact takes place between all of the balls and the ball seats. In each bearing the balls 19 are arranged in alignment transversely to knife edge 16, permitting some slight sidewise tilting of the platform on balls 19 while balls 17 between the bearing members 18 and 14 are not arranged to permit of a relative tilting between the members 14 and 18. Since the bearing member 14 may rock in one direction over the knife edge 16 and the platform and bearing member 20 may rock transversely to such movement over the balls 17, a slight universal movement of the platform without disturbing the supporting levers is provided for.

The main supporting levers 13 are provided with knife edges 20 extending across the split or forked ends of the levers and resting on the main lever bearing stands 21, and at their inner ends are provided with link connections 22 to transverse levers 23. By this means the inner ends of each pair of main levers 13 are connected to one common transverse lever 23. These in turn are connected in pairs by loops 14 (Fig. 3) to end extension levers 24 and are supported by knife edges 25 resting in the bearing stands 26. The fulcrums of the end extension levers 24 are in the knife edges 27 (Fig. 3) resting in the bearing stands 28 mounted on the concrete piers 29. The end extension levers 24 in turn have a link or loop connection 30 with middle extension levers 31 (Fig. 4). The middle extension levers are supported at their centers, to have a non-multiplying effect, by knife edges 32 carried in said levers 13.

and resting on the bearing stands 33 mounted on piers 34. The inner ends of the two middle extension levers 31 have link or loop connections 35 with a double loop 36 by which, as shown in Fig. 8, they are connected to transmit motion to a fifth lever 37, the latter being pivotally supported on its stand 38 and having steel yard rod connections 39 to a shelf lever 40, which in turn is connected by the beam rod 41 to the usual scale beam 42.

The live rail openings 6 in platform 4 are as usual provided with upwardly extending flanges 43 (Fig. 10) at their sides to prevent dirt from working into the scale pit. The live rails 8 carry dirt shield supports 44 properly constructed to provide seats for angle irons 45 carried by dirt shields 46. The inner ends of the dirt shields bear upwardly on the underside of the head. By this arrangement the dirt shields may rest at a maximum height above the flanges or guard angles 43, permitting all necessary relative movement between the rails and the rigid deck 4. The dirt shields may freely rock upwardly if coal or other matter becomes lodged between the outer ends 47 of the dirt shields and deck 4 and under such circumstances the indication of the proper weight is not materially affected.

It may be seen from Fig. 6 that the main bearings 12 of the scale platform are located outside of the vertical plane of rails 8 and also that rail stands 7 are suitably constructed to resist downward pressures exerting obliquely toward the sides of the scale. Considerable trouble in rail scales has resulted from placing the main platform bearings directly below the live rails, as any slight displacement of the latter may cause the load to carry more or less outside of the main bearings, racking the entire structure and making it inaccurate.

The middle extension levers 31, as stated and shown in Fig. 4, have fulcrums midway of their lengths and do not carry an undue load as a high multiplication is provided in the main lever.

In the operation of the device, a load to be weighed by the scale is balanced by means of the usual weighing mechanism at the scale beam 42 and the system of levers connecting said beam with the scale platform. The lateral and longitudinal movements of the scale platform when cars are run thereon is limited by the ball recesses in bearings 12. If the platform tends to rock laterally in the direction of the length of knife edges 16 on main levers 13, the upper aligned set of balls 19 provide for permitting such movement without transmitting it to the main levers while the lower set of balls 17, by transmitting the weight of the platform to the bearing member 14 at four points, prevents said bearing member from tilting on knife edge 16. Movement of the main levers

caused by a weight on the scale is transmitted by the transverse levers 23 to the end extension levers 24, the latter by their link connections communicating the movement to the non-multiplying levers 31, which in turn communicate the motion to the fifth lever 37. Thus, the motion which occurs in the eight main levers, through a weight applied on the platform, is finally transmitted to the single lever 37 which is connected in the usual manner to the scale beam 42.

From the foregoing, it may be seen that the present invention provides a scale having many refinements of construction not occurring in scales at present in use, and such features may be applied to advantage to many types of platform scales.

Although but one specific embodiment of this invention has been herein shown and described, it will be understood that numerous details of the construction shown may be altered or omitted without departing from the spirit of this invention as defined by the following claims.

I claim:

1. A weighing scale comprising walls forming a scale pit, multiplication levers fulcrumed in said pit and having connections for operating a scale beam, a platform supported by said levers, and a plurality of superposed ball bearings between said levers and platform.

2. A weighing scale comprising walls forming a scale pit, a platform supported therein, the supports for said platform including a plurality of pairs of multiplication levers extending longitudinally of the platform, common transverse levers, each of said pairs of multiplication levers being fulcrumed near their outer ends and connected at their inner ends to said common transverse levers, said transverse levers having connections for operating a scale beam.

3. A weighing scale comprising walls forming a scale pit, a platform supported therein, the supports for said platform including a plurality of pairs of multiplication levers extending longitudinally of the platform, common transverse levers, each of said pairs of multiplication levers being fulcrumed near their outer ends and connected at their inner ends to said common transverse levers, said transverse levers having connections for operating a scale beam, said connections including end extension levers and non-multiplying middle extension levers respectively.

4. In a railway track scale, the combination of a scale beam, a platform, supports for said platform having connections for operating the scale beam, rails on said platform, a rigid deck having rail openings, and dirt shields pivoted to said rails and extending over said rail openings.

5. A weighing scale, comprising a scale

beam, a platform, levers supporting the platform and having connections to operate said beam, ball bearings between said platform and supporting levers, knife edges between said bearings and levers, said ball bearings comprising superposed sets of balls with a free ball seat between, one of said sets of balls consisting of a single row extending transversely to the corresponding knife edge.

3. A weighing scale, comprising a scale beam, a platform, levers supporting the platform and having connections to operate said beam, ball bearings between said platform and supporting levers, knife edges between said bearings and levers, said ball bearings comprising superposed sets of balls with a free ball seat between, one of said sets of balls consisting of a single row extending transversely to the corresponding

knife edge, and said free ball seat comprising a plurality of relatively movable sections for insuring distribution of the weight carried through all of the balls of the bearing.

7. In a weighing scale, a scale beam, a platform, levers connected to operate said scale beam and having bearings for supporting said platform, said platform comprising a plurality of sections having connections permitting slight relative movement between the sections, said connections being located immediately above said bearings.

Signed at Chicago this 13th day of November 1914.

RUDOLF GRUNDMAN.
